UNITED STATES PATENT OFFICE.

CHARLES E. GUELICH, OF KINGSTON, PENNSYLVANIA, ASSIGNOR TO GUELICH PAVING PROCESS COMPANY, OF HURON, SOUTH DAKOTA, A CORPORATION OF SOUTH DAKOTA.

ASPHALT DRYING, HEATING, AND MIXING PLANT.

1,190,642.

Specification of Letters Patent. Patented July 11, 1916.

Application filed October 24, 1911, Serial No. 656,490. Renewed December 30, 1915. Serial No. 69,504.

To all whom it may concern:

Be it known that I, CHARLES E. GUELICH, a citizen of the United States, and a resident of Kingston, in the county of Luzerne and 5 State of Pennsylvania, have invented certain new and useful Improvements in Asphalt Drying, Heating, and Mixing Plants, of which the following is a specification.

This invention relates to improvements in 10 asphalt drying, heating and mixing plants, and it especially relates to portable plants for paving and other purposes.

While the invention is particularly adapted to the production of asphalt mixture, it 15 is, of course, not restricted to cases in which asphalt or its products is used, but can be employed in the productions of many products of concrete or other plastic material, in which drying and mixing of the ingredients 20 are required.

A continuous asphalt drying, heating and mixing plant, broadly considered, requires the following elements among others:— 25 a drier to dry the aggregates before delivery to the mixer; a mixer and cooker to thoroughly mix, cook and incorporate the dried aggregates with the molten asphalt; devices for automatically conveying the dried aggregates to said mixer; devices for supplying proper quantities of the molten asphalt to the aggregates in the mixer; and controllable motor agencies for imparting the proper motions to the mixer, the drier, 30 the conveyer and other parts of the apparatus in harmonious relation. If the apparatus is portable, then the installation should also include devices by which the motor can be made to drive the vehicle upon 35 which the apparatus is mounted.

40 It is the aim of the present invention to render the operation strictly and automatically continuous; to greatly increase the output of the installation; diminish the liability of clogging the mixer, driers or conveyors; and place the whole more perfectly 45 under control of the operator.

To these ends the invention, among other important points, relates to a mixer and cooker consisting of a rotary chamber arranged to be practically closed during the operation of mixing and cooking, whereby such chemical changes are produced in the asphalt and the aggregates, one or both, that the asphalt actually impregnates the 55 particles of aggregates. Whereas in the art

as heretofore practised the particles of the aggregates have been coated with the asphalt, in my invention the particles of the aggregates are actually penetrated throughout and impregnated by the asphalt, and a 60 far superior "mix" for paving and other purposes is thereby obtained.

The invention further relates to the operative combination with a mixer and cooker of a plurality of driers, since I have 65 found that in the operation of such plants this produces a very great increase in the output.

The invention further includes the combination with the mixer and the driers of a 70 circumferential elevator-conveyer, arranged so that a single-elevator conveyer having a continuous motion will serve all the driers. In this respect my invention has a capacity 75 and operates with a simplicity of construction exceeding what has ever before been accomplished in this class of apparatus.

The invention further includes the construction of the mixer, whereby proper motions of the mixer and its devices are attained, and the smoothest possible interior is produced; the liability of material sticking to and burning on, and gradually clogging the mixer being reduced to a minimum, and the regularity and success of the 85 mixing operation being promoted.

The invention also relates to the construction of the driers, and the means for imparting the proper motions to the driers.

The invention also relates to the circumferential elevator-conveyer, and its operative connections with the driers and the mixer, as will be hereinafter more fully set forth.

The invention also relates to the worm 95 feed and associated parts, whereby the dried aggregates and the molten asphalt are fed in suitable regulated quantities to the mixer.

The invention also relates to the various controlling devices, whereby in case of need, 100 the several parts may be independently started or stopped.

The invention also relates to the devices for propelling and for controlling the propulsion of the truck on which the apparatus 105 is mounted.

The invention also relates to other parts, and combinations, as will be apparent from the description and the claims hereinafter contained.

Referring to the drawings which accompany the specification, to aid the description, Figure 1, (Sheet 1) is an elevation of the rear, or supply, end of the machine. Fig. 5 2, (Sheet 2) is an elevation of the front, or conveyer, end thereof. Fig. 3, (Sheet 3) is a longitudinal vertical section of a drier and certain other parts, and of certain gearing. In this view, also, the mixer, 10 fuel oil tank and other parts are shown in elevation. Fig. 4, (Sheet 1) is a cross section of a drier. Fig. 5, (Sheet 4) is a vertical longitudinal section, on a large scale, of the mixer and its hopper, and showing 15 the worm feed and mixing blades in elevation. Fig. 6, (Sheet 4) is an end view of the mixer, with a head removed, and showing the mixing blades. Fig. 7, (Sheet 4) is a detail of the mixing drum and the housing. Fig. 8, (Sheet 5) is an end elevation of certain gearing, certain of the gears being indicated conventionally. Fig. 9, (Sheet 5), is a plan of said gearing, and showing the worm feed. Fig. 10, (Sheet 2) is a longitudinal vertical section, as on the line 10—10 of Fig. 11, and on large scale, of the worm feed and casing therefor, and showing the chambers both for the aggregates and for the asphalt; Fig. 11, (Sheet 2) being an elevation looking at the left end of 20 said casing. Fig. 12, (Sheet 6) is a transverse vertical section of the fire box, the fire brick being however shown only in one compartment, for simplicity of representation. Fig. 13, (Sheet 6) is a side elevation of the fire-box. Fig. 14, (Sheet 6) is a broken top view of the housing, indicating the smoke stack, the flue, and controlling dampers therefor. Fig. 15, (Sheet 25) 40 is a vertical cross section of the base of the stack and the flue. Fig. 16, (Sheet 7) is a broken plan view on large scale, of the vehicle driving and steering gear. Fig. 17, (Sheet 1), is a sectional detail, on large 45 scale, of mixer door. Fig. 18, (Sheet 8), is a broken longitudinal section and elevation of preferred construction of a shield for the mixer. Fig. 19, is a vertical cross section on the plane of the line 19—19 of 50 Fig. 18. Fig. 20 is a broken detail of said shield in elevation.

The housing and fire box.—Various parts of the apparatus are set in a sheet metal housing A, (Figs. 1, 2 and 3) suitably constructed with uprights and horizontal beams a', a' on a truck B. The interior of said housing A is connected with and heated by the furnace or fire-box F, (Figs. 12 and 13). On top of said housing A is a 55 smoke stack S, the base of which communicates with a longitudinal flue f carried along inside the top of said housing and nearly to each end thereof. The ends of said flue f are open and communicate with the interior of said housing near the ends thereof,

so that a single flue serves to produce a proper movement and distribution of the products of combustion through said housing and toward both ends thereof; and said flue is controlled by dampers d, (Fig. 14) 70 operated from the outside of the top of the housing by handles and rods d'. Said fire-box F (Figs. 12 and 13) consists of a sheet metal casing or shell, preferably of the shape shown, properly suspended on the truck B below the said housing A, and preferably formed with two divisions or furnaces. Said divisions or furnaces are respectively connected by suitable openings with the interior of the housing. Said fire-box contains perforated fire brick f', (Fig. 12), forming a longitudinal chamber with numerous lateral openings, and an oil burner B' projects a flame under air or steam pressure into said fire brick, in the known manner, producing intense heat; the products of combustion ascending into said housing A, and heating the drier, the mixer, and the asphalt tanks. There will preferably be a burner for each furnace, supplied with oil by pipe b', controlled by a valve from an oil tank T, mounted on top of said housing A, (Fig. 3). Said housing A may be constructed of any suitable materials. But I prefer to construct it of an outer 90 and inner steel plate, respectively 1 and 2, in Fig. 7, with a layer of asbestos fabric 3, between the plates; for, by this construction, the housing is rendered an excellent nonconductor of heat. The mixer M and the driers D, D, or their heads, may require to pass through the housing wall, and I prefer to make the joints by placing annular flanges 4 and 8 on said heads, positioned to wipe against said outer steel plate 1 as the mixer, or the driers revolves, (Figs. 5 and 7).

The driers.—There are two similar driers, D, D each arranged to supply dried aggregates to the same mixer M, and adjacent to opposite sides thereof, (Fig. 1). Each said drier D consists of a shell 5, and placed at a suitable inclination with the horizontal, to effect the proper longitudinal feeding of the contents from the receiving to the delivering end, and fixed concentrically at the receiving end to a head 6, and at the opposite end to a spider 7, keyed on the shaft 9, by which the drier is rotated; said shaft 9 having a gear meshing with a gear train, whereby said shaft 9 is driven from the prime motor, as will be hereinafter more fully explained. Another spider 11, keyed on the end of said shaft 9, secures said shaft to said shell 5 in proper alinement. Longitudinal flanges or ribs 12, (Fig. 4), fixed to the inside of said shell 5, serve to thoroughly stir up and pitch about the aggregates. Said aggregates, consisting of a mixture of broken stone, sand, or of any other desired 125

materials, having been suitably mixed together, are dumped into the hopper D', the throat D² of which delivers through said head 6 into said drier D; said throat D² being provided with a circular flange 14 concentric to said head 6, and working in an annular concentric groove of said head, 15 being an annular flange plate positioning said flange 14 in said groove. The flange 10 of said head 6 is supported on rollers 16, (Fig. 1). Said hopper D' is fixed to the upper end of said throat D², and the whole is rigidly supported on the housing floor by the bracket D³. The inclination and the rotation 15 of said drier D causes the aggregates to feed gradually down grade toward the discharge end of the drier, the inclination and rotary speed being adjusted to subject said aggregates to the drying action for the proper time. Finally the dried aggregates 20 are discharged from the drier and by the chute D⁵, (Fig. 3), upon the elevator conveyer, by which said aggregates are conveyed to the proper chutes or hoppers, and delivered to the worm feed, whereby they 25 are supplied regularly and in proper quantities to the mixer.

The elevator conveyer.—Said chute D⁵ delivers said aggregates through the boxing 30 18, which incloses the bottom and sides of the lower part of the elevator conveyer and to said elevator conveyer. Said elevator conveyer consists of parallel wire or chain cables 19, 19, provided with elevator buckets 35 20, (Figs. 2 and 3), traveling in the direction of the arrows. Said elevator conveyer, (which I shall from time to time herein-after designate simply as the "conveyer"), is suitably guided around chain wheels 22, 40 properly supported in bearings adjacent to the four corners of said housing A, so that said conveyer, as it were, passes around said housing. I indicate this arrangement by the term "circumferential conveyer," or 45 "circumferential elevator conveyer," and it is an important part of my invention, since it enables a single conveyer to serve several driers and deliver the aggregates to several chutes, and with one continuous direct motion 50 of the conveyer. The result is a greatly increased conveyer capacity, and in a strictly continuous operation. Said conveyer is conveniently driven by employing one of said chain wheels 22, or rather a pair 55 of them on a single axle, as the driver, for example the upper right hand pair in Fig. 2; it being understood that all said wheels 22 are arranged in pairs fixed on short axles, so that one wheel guides and supports a 60 chain or cable at each side of the conveyer. The shaft 23 is provided with a suitable pulley driven by an endless chain 24, which is in turn driven by a pulley fixed on a shaft 25, which has a similar fixed pulley driven 65 in its turn by chain 27, from pulley 28 on an

axle 29, driven by suitable gearing from the prime motor and at the proper speed. The aggregates having been delivered on the bottom of said boxing 18, the buckets of the conveyer, traveling practically in contact with said bottom, scrape up and push along said aggregates until the buckets turn right side up at the corner of the housing and ascend more or less full of the aggregates. As the buckets near the top of their travel 70 they enter a boxing or casing 30, which extends across over the housing A and has a horizontal floor 31 extending from journal to journal of the upper wheels 22. As the buckets turn at the upper left hand wheel 75 they dump the aggregates onto said floor 31, which is provided with two pivoted doors 33, each of which communicate with its respective compartment 34, or 35, of a chute 36 which delivers the aggregates into the 80 worm feed casing W'. The pivot rods 38 of said doors 33 are extended out through the boxing 30, with suitable arms on the outer ends connected by a hand lever so that the attendant by one lever can actuate both 85 doors. Said doors are normally set so that when one is closed the other is open. The aggregates being dumped upon the said floor 31, the tilted buckets traveling practically in contact with said floor push the aggregates along, and they fall, by whichever door 33 is open, into the proper compartment of said chute 36, and thence to the worm feed casing. Said compartments have 90 sliding gates at the bottom opened and operated by the attendant. If it is desired, at any time, to discharge the aggregates into chute 40, both doors will be closed by disconnecting the operating levers, and the buckets will then push the aggregates into 95 said chute 40, the valve which normally closes its upper end being now opened. The buckets having emptied their contents upon 100 said floor 31, turn downward at the upper right hand corner, at the said driving wheel, and descend again into the boxing 18, 105 again traversing through said boxing, being filled, ascending, dumping their contents again on floor 31, and so on continually.

The worm feed.—Each of said compartments 34, 35 of said chute 36 communicates at its lower end with the hopper w of the worm feed casing W', (Figs. 2 and 10). Said casing is provided with the larger cylindrical chamber 41, within which is the worm W on the worm shaft w², driven by suitable gearing from the prime motor; and also with the asphalt passage 42 communicating with the lower end of a pipe 44, (Fig. 3), controlled by a valve 46, and leading 115 from the asphalt measuring tank 47, in which the molten asphalt is placed from the asphalt tanks K, K. Said worm W should be of substantially less diameter than said chamber 41, in order to prevent clogging 120 125 130

and breakage. Said worm casing W' enters concentrically, with working fit, through the head M² of said mixer M, a flange ring 48 bolted to said head M², (Fig. 5), serving to close the joint and prevent the displacement, of said worm casing as the said mixer revolves. The worm W feeds the aggregates, in proper quantities, into the mixer; the inner end of the said worm casing W' being cut away, forming a lip 50 which effects the abrupt fall of the aggregates into the mixer just before they begin to be mixed with the molten asphalt. A measured quantity of asphalt is put in said tank 47, and the attendant, by operating said valve 46, regulates the supply of the asphalt to the mixer by the said channel 42, so that the asphalt and the aggregates drop practically together into the mixer M without danger of clogging the worm.

The mixer.—Said mixer M consists of a cylindrical metal shell set eccentrically between two heads M¹, M², (Fig. 5). The shell has opposite eccentricity, with respect to the two heads, which are set concentrically on a horizontal line with each other, so that the mixer as it rotates, acquires a rolling and tumbling motion. Said mixer shell is made as smooth as possible on the inside; great care being taken that rivet heads shall be sunk flush, seams carefully butted, and the like, so that said shell shall not catch up the contents, as a rough shell would. This is a valuable feature of my apparatus, for it materially diminishes the sticking of the contents to, and their burning on the shell, and the gradual impairment of operation, and clogging of the shell. The said heads M¹, M² are each flanged, and part of the flange of head M² is provided with gear teeth meshing with and driven by gear 98, which is in turn driven from the prime motor. The flange of said head M¹ is supported on rolls 58, and the untoothed part of the flange of head M² is supported on rolls 59, (Figs. 1 and 5). Transverse blades P, P extending partly across the interior of the shell, are secured in position by being fastened transversely to rods 52, which extend from end to end of the shell, being fastened to said heads M¹, M² by angles as indicated; and said blades P, P are turned at such an angle to the axis of the shell that, as the shell rotates and tumbles, said blades serve both for mixing the contents and for propelling them longitudinally toward the discharge end of the mixer. And I find that the worm feed, the rotation and tumbling of the shell, and the effect of the inclined blades produce a regular movement of the contents from the inlet to the discharge end of said mixer; the rotary speed and the propelling action being such, as to subject the contents of the mixer to the mixing action for the proper time. The dis-

charge head M¹ of said mixer is provided with a hinged door M³, (Figs. 1 and 17), equipped with a pivoted spring latch 54, which normally holds said door M³ closed. But the attendant by striking said latch with a hammer shifts it so that the door can open as the mixer revolves, the door then swinging full open and being caught by the catch 55, and held open until released by the attendant. Now, when the mixer revolves to such position that the door opening is lowermost, the contents of the mixer discharge by the chute 56, to carts or to any other receptacle. A suitable clutch herein-after more precisely referred to enables the attendant to stop the mixer, whenever he wishes, without stopping other parts of the apparatus; and other suitable clutches provide for independently stopping and starting the worm feed and other parts of the apparatus. I prefer to provide a small orifice 57, covered by a movable flap 57^a in the center of said head M¹, (Fig. 2) for escape of vapor, inspection and other purposes. During the operation of cooking and mixing, said mixer M is closed practically tight, because, at the inlet end, the aggregates fill and close the chamber 41 as they are pushed and more or less compressed by the worm W, and the asphalt fills and closes the channel 42, and because, at the outlet end, the dust and condensable vapors form a practically gas tight packing around the lip of said door M³, and said flap 57^a will be normally closed. In the said closed mixer the temperatures and gaseous pressures become relatively high, with chemical changes in the asphalt and rock of the aggregates, which is preferably a lime stone, and the asphalt, as hereinbefore stated, thoroughly penetrates and impregnates particles of stone. My closed mixer also greatly improves and rejuvenates inferior or old asphalt, by employing proper oil mixtures, and said closed mixer is an important element of my invention.

I prefer to place a deflecting shield around the lower part of the mixer M, to permit of cutting off the heat from said mixer in case it is desired to use or heat only the driers. This shield is however, not indispensable and is illustrated only in Figs. 18, 19 and 20, wherein it is shown constructed of curved metal plates I, I', with a layer of asbestos J between, properly stiffened by ribs H and suspended from rods h, h. Said shield is provided with openings y protected by slides x operated from outside said housing A by suitable rods and handles. When said slides x are opened the hot products of combustion pass through said opening y and heat said mixer. When said slides are closed the mixer is cut off from the heat, and the driers only may be heated.

The asphalt tanks.—I greatly increase the

output and render the operation absolutely continuous by employing two asphalt tanks, K, K, indicated in Fig. 1, each arranged for convenience practically vertically above a 5 drier D, D. Said tanks, of suitable shape and size, are solidly supported on the top frames of the housing A, with their bodies projecting downwardly into the aforesaid flame chamber of said housing A, so that 10 the same flame which heats the driers and the mixer melts the asphalt. Thus a single oil burner, or a pair of burners, if there are two furnaces, serves for the several purposes of drying the aggregates, heating the mixture of aggregates and asphalt, and melting 15 the asphalt, and this is an important feature of my invention. Each of said tanks has a cover 60, provided with a strong hinged lid 61, to permit of filling the tank 20 with the asphalt, and also to permit the drawing off of the molten asphalt from the tank into the aforesaid measuring hopper 47. During the melting of the asphalt, said lids 61 will be closed, except when, from 25 time to time as necessary, one is opened to ladle out the molten material into said hopper 47; and I prefer to take asphalt from said tanks alternately, whereby one tank is always full and hot, during a job. A 30 suitable pump may be employed to pump the molten asphalt from the tanks K to the measuring hopper 47.

The motor truck.—I prefer to mount my apparatus on a motor-truck, deriving the 35 power to run the truck from the same prime mover as drives the various parts of the apparatus. A gear 80, (Fig. 16) loose on shaft 71 meshes with a gear 72, (Fig. 8) which is, in turn, driven by gear 73 on engine 40 shaft E. A clutch 75, (Fig. 16) operated by the engineer, through suitable clutch lever, serves to connect and disconnect said gear 70 with and from said shaft 71. A beveled pinion 76 on said shaft 71 meshing 45 with a beveled gear 77 fixed on a counter shaft 78 drives said shaft 78 and chain wheels 79 fixed thereon, and endless chains 80 from said wheels 79 drive large chain wheels 81 adjacent to the truck wheels 83 50 fixed on the truck wheel shaft 82; and thereby the truck is propelled as desired.

To steer the truck, the rear wheels and adjacent parts of the truck are constructed and arranged as follows: On the under side 55 of the truck frame 80, equi-distant from and at opposite sides of the king bolt 87, are secured circular segments 88, (Fig. 16), which rest on rollers 84 carried in stout uprights on the bolster 85 of the rear axle 60 86. Said king bolt 87 passes down through a plate, which is fixed to said truck frame, into the said axle bolster 85, (Figs. 1 and 3). Said bolster 85 is provided with a toothed segment 90, meshing with a worm 65 91, on the axle of which is fixed a gear 92,

meshing with a pinion 93 fixed on a horizontal transverse shaft 94 turning in bearings in the truck frame and having a hand wheel 95 on the outside of the truck, which can be readily operated by a man running 70 or walking alongside of said truck as it travels. Thus a man on the road can readily steer the machine in any desired direction.

The prime motor and gearing.—An important, but not an essential feature of my 75 invention, is the combination and arrangement of parts by which a single prime motor supplies all the motive power, both for working the apparatus and for propelling the truck. I prefer to employ a steam boiler 80 with oil fuel or a gas engine, but of course any suitable type of boiler and engine might be used. On the main engine shaft E, (Figs. 3 and 9) is said gear 73 meshing with said gear 72; and that meshing both with aforesaid wagon gear 70 and with gear 96 which drives said shaft W² of said worm feed W. Said gear 72 has a clutch 114 for driving shaft 97, which has at its other end gear 98, which drives the gear on the head M² of 90 said mixing drum, (Figs. 5, 8 and 9). A small gear on said shaft 97 meshes with two similar gears 99 respectively on the counter shafts 100, and small gears 101, on said shafts 100 mesh with large gears 102 fixed 95 on and driving the said shafts 9, 9 of the respective driers.

The clutches.—Said gear 96, loose on the said worm feed shaft w² is connected with one member of clutch 110, the other member of which is fixed on said shaft w². Thus by throwing said clutch on or off, said worm feed is stopped or started independently of the mixer. Said gear 98 is loose on shaft 97, and connected by a sleeve with one member 105 of a clutch 112, (Fig. 9). The other member of said clutch is secured to said shaft 97. Thus by throwing said clutch 112 on or off, the mixer can be started or stopped independently of other parts of the apparatus. Said gear 72 is loose on said shaft 97 and connected with one member of the main clutch 114, the other member of which is fixed on said shaft 97. Thus by throwing 110 said clutch 114 on or off, the apparatus generally may be started or stopped; and while said clutch 114 is on, the said other clutches 75, 110, 112 provide for independently stopping or starting the truck, the worm feed and the mixer, and the several clutches give 115 the attendants complete control over the several parts of the machine. The aforesaid clutches may be of any suitable kind, and I prefer to use friction clutches provided with springs acting to draw the members of the 120 clutch into operative connection. Clutch 114 may however be of the toothed variety.

Now having described my improvements, I claim as my invention.

1. The combination in apparatus of the 120

kind specified, of a mixer and a plurality of driers, a conveyer in operative communication with each said drier, a plurality of compartments for dried material in operative connection with said mixer, and a closure for said compartments whereby each said compartment may independently receive dried material from said conveyer.

2. The combination in apparatus of the kind specified, of a mixer, a plurality of driers adapted to supply dried aggregates for said mixer, a chute provided with a plurality of compartments, one for each said drier, and all said compartments being operatively connected with said mixer, means to close the inlet of one or the other said compartment, and a conveyer adapted to convey dried aggregates from one or the other drier to one of said compartments, whereby either of said driers may be operated singly.

3. In apparatus of the kind specified, the combination with a rotary mixer of a worm-feeding device operatively connected with said mixer and comprising a channel for aggregates and a feeding worm therein, and a separate channel for molten asphalt extending inwardly slightly beyond said channel for aggregates, whereby said aggregates and said molten asphalt begin to mix as they enter said mixer.

4. The combination in apparatus of the kind specified, of a mixer and a plurality of driers, a housing containing said mixer and driers, a single furnace or set of furnaces arranged to heat all said driers and mixer, means to deliver dried aggregates from either drier to said mixer, and means to mix molten asphalt with said aggregates as they enter said mixer, and a circumferential con-

veyer adapted to convey the dried aggregates from each drier.

5. The combination in apparatus of the kind specified, of a rotary mixer, a plurality of rotary driers in operative connection therewith, whereby one or the other of said driers may be inoperative without stopping the feed of materials to said mixer, and a worm feed device operatively connected with said mixer, and provided with a channel for aggregates and with a separate channel for molten asphalt.

6. The combination in apparatus of the kind described, of a housing, a rotary mixer in said housing having a smooth shell, blades in said mixer supported independently of said shell and separated therefrom, a plurality of rotary driers in said housing, means for feeding material to said mixer, and an elevator conveyer adapted to convey dried material from all of said driers to said feeding means.

7. In apparatus of the kind specified, the combination with a mixer and a plurality of driers, of a plurality of compartments for feeding material to said mixer and means for closing the inlet of one or another of said compartments, and a conveyer adapted to convey material from said driers to one or the other of said compartments, whereby one or the other of said driers may be inoperative as desired.

Signed at Wilkes-Barre, in the county of Luzerne, and State of Pennsylvania, this 20th day of October, A. D. 1911.

CHARLES E. GUELICH.
